(57) CLAIM

What is claimed is the ornamental design for a pocketed golf towel, as shown and described.

DESCRIPTION

FIG. 1 is a top, right side perspective view of the invention;
FIG. 2 is a right side view thereof;
FIG. 3 is a left side view thereof;
FIG. 4 is a rear end view thereof;
FIG. 5 is a front end view thereof;
FIG. 6 is a top view thereof;
FIG. 7 is a bottom view thereof; and,
FIG. 8 is a bottom front perspective view with an opening of the device in an open position exposing a the pocket for insertion of an object for cleaning or polishing.
The phantom or broken line showing is for illustrative purposes only and forms no part of the claimed design.
The right and left sides of the device are mirror images of one another.
